FUEL MIXER FOR INTERNAL-
COMBUSTION ENGINES

Joseph Reindl, Topanga, Calif.

Application June 27, 1949, Serial No. 101,636

2 Claims. (Cl. 48—180)

1

The present invention relates generally to gaseous fuel mixers for internal combustion engines; and is more particularly concerned with devices of this kind wherein a vortex or whirling action is imparted to the gaseous mixture prior to delivering to the engine.

It is one object of the herein described invention to provide a device which is simple in construction, inexpensive to manufacture, and efficient in operation, the device being adapted to be interposed between the intake manifold and carburetor of a gas engine for the purpose of producing a more thorough mixture of the fuel and air, with the result that more efficient engine operation will be obtained and maximum power will be developed with a minimum consumption of fuel.

Still another object is to provide a simple device for the above stated purpose which is devoid of any moving parts that might wear out, become detached in use and be drawn into the engine with damaging effect; which will operate efficiently at high engine speeds without choking the flow of fuel admixture; and which will operate in such manner that recondensation of the mixed fuel will be avoided.

Further objects of the invention will be brought out in the following part of the specification, wherein detailed description is for the purpose of fully disclosing the invention without placing limitations on the scope of the invention defined in the appended claims.

Referring to the drawings, which are for illustrative purposes only:

Fig. 1 is a longitudinal section through a connection joint between the intake manifold and carburetor for supplying fuel to an internal combustion engine showing a device embodying the features of the present invention mounted therein;

Fig. 2 is a sectional view taken transversely of the same, the section being taken substantially on line 2—2 of Fig. 1; and

Fig. 3 is a vertical section through the device of the present invention, taken substantially on line 3—3 of Fig. 2.

For purposes of illustration, the drawing illustrates a device as generally indicated at A embodying the features of the present invention, this device being operatively associated with a fuel conducting connection between a conventional carburetor (not shown) and the intake manifold (not shown) of an internal combustion engine.

More specifically, the fuel connection is shown

as including a carburetor connection 10 and an inlet manifold connection 11 in the form of fuel conducting pipes joined by conventional joint flanges 12—12. As in the conventional joint, the flanges 12—12 are secured in confronting faced relation and clamped together by suitable clamping bolts 13—13, the usual sealing gasket 14 being interposed between the flanges to prevent leakage.

10 A device of the present invention is constructed so that it may be readily attached and removed without the necessity of having to provide additional connectors or securing means, and advantage is taken of the usual joint flange construction to provide a support for the mounting of the device.

As shown, there is provided a thin plate or gasket 15 of suitable material, having a peripheral configuration similar to that of the sealing gasket in order that the sealing gasket and gasket 15 may be mounted in the joint in superposed relation, as shown.

The gasket 15 is centrally provided with a fluid flow passage or opening 16 of a diameter corresponding with the internal diameter of the connections 10 and 11 so that, when the gasket 15 is mounted in the joint, the passage 16 will be axially aligned and in registration with the internal bores of the connections 10 and 11.

20 A spirally formed blade 17 is supported from the gasket 15, this blade being constructed of suitable material as by twisting a flat rectangular strip or otherwise forming the blade with a 90° twist between its ends 18 and 19, so that end edges will be formed which are angularly positioned about a longitudinal axis in 90° relationship. One end of the spirally formed blade 17, in this case end 18, is inserted into the fluid flow passage or opening 16 and secured as by welding at points 20—20 to rigidly support the blade in a position extending outwardly from one side of the gasket 15.

In Fig. 1, the spiral blade 17 is mounted so as to extend in a down stream direction. The device, however, will operate with the same efficiency when installed in a fuel connection so as to extend upstream from the gasket 15.

From a consideration of the device as described above, it will be seen that the action of the spiralled blade 17 is to rotate the fuel stream through an angle of 90° as it passes from one end of the blade to the other, and that in accomplishing this twisting effect, the cross-sectional area of the stream is reduced only to the extent of the cross-sectional area of the material

2

forming the spiralled blade. In other words, any choking tendency is reduced to such small value that it has little if any practical effect upon the free flow of the stream. I have determined that the efficiency and success of my device results from a whirling or twisting movement which is imparted to the fuel stream, and that this will result in a more thorough mixing of the fuel and air and that this will give more efficient engine operation and greater power will be developed with a minimum consumption of fuel.

Further, I have determined that the length of the spiralled plate in relation to its diameter is a critical consideration, and that the most efficient and best operation is obtained when the length of the spiralled plate between its ends is substantially 1.1 times the diameter of the passage 16 or the bore of the fuel connection in which the device is mounted.

While the twist of the blade has been described as being 90°, it should be noted that the amount of twist is very critical and when the twist is varied in excess of two degrees either way from 90°, there is a material change in the efficiency of operation of the device. The twist of the blade, for best operation, should therefore be maintained within the limits of 88° to 92°.

I claim as my invention:

1. A fuel mixing device for internal combustion engines adapted to be mounted in the fuel intake passage of the engine, comprising: a spi-

rally formed blade having an end-to-end length substantially equal to 1.1 times the blade diameter, said blade being spirally formed and having substantially a 90° twist; and means for securing said blade within said intake passage so that said blade extends longitudinally thereof.

2. A fuel mixing device for internal combustion engines adapted to be introduced into a flanged joint in a connection between a carburetor outlet and manifold intake of the engine, comprising: a mounting gasket adapted to be firmly clamped between the flanges of said joint, said gasket having a central fuel passage; and a spirally formed blade having substantially a 90° twist rigidly secured to said gasket with one end diametrically spanning the fuel passage of said gasket so that the blade projects on one side of said gasket in axial alignment with said fuel passage, said spiral blade having an end-to-end length substantially equal to 1.1 times its diameter.
